UNITED STATES PATENT OFFICE.

EMIL TESKA, OF RACINE, WISCONSIN.

BUTTON.

1,215,217.

Specification of Letters Patent.

Patented Feb. 6, 1917.

Application filed June 13, 1916. Serial No. 103,508.

To all whom it may concern:

Be it known that I, EMIL TESKA, a citizen of the United States, residing at Racine, in the county of Racine and State of Wisconsin, have invented certain new and useful Improvements in Buttons; and I do hereby declare the following to be a full, clear, and exact description of the invention, such as will enable others skilled in the art to which it appertains to make and use the same.

My invention relates to new and useful improvements in buttons and more particularly to that class adapted to be secured to garments and my object is to provide a removable stem for the button which is adapted to be introduced through the goods.

A further object is to provide a plate to receive the inner end of the stem.

A further object is to provide means for holding the plate rigidly upon the stem.

And a further object is to provide a spring latch having arms thereon adapted to interlock with parts of the stem.

Other objects and advantages will be hereinafter set forth and more particularly pointed out in the accompanying specification.

In the accompanying drawings which are made a part of this application,

Fig. 1 is a front elevation of the button showing the same attached to parts of a garment.

Fig. 2 is a similar view of the reverse side of the button.

Fig. 3 is an enlarged inner end view of the stem of the button and anchoring means therefor.

Fig. 4 is a sectional view through the outer end of the stem showing the anchoring means in engagement therewith.

Fig. 5 is an enlarged central sectional view through the button and anchoring means showing the same attached to parts of a garment, and

Fig. 6 is a central sectional view through the anchoring means.

Referring to the drawings in which similar reference numerals designate corresponding parts throughout the several views, 1 indicates a piece of fabric which may consist of any preferred material, and 2 indicates the button proper which may be designed in any preferred shape and contour, said button having a circular rib 3 on its inner face and at the central portion of the button, an opening 4 being formed through

the button and through the rib for the reception of a stem 5.

The outer end of the stem 5 is provided with a head 6, while the opposite end thereof is preferably rounded or pointed, so that it will readily pass through the fabric. In order to form an anchoring base for the end of the stem 5, a plate 7, preferably in the form of a disk, is introduced over the inner end of the stem and rested against the inner face of the fabric, said plate having a channel 8 around its edge in which is seated a spring latch 9, said latch being formed preferably of spring wire, the free ends of which are formed into arms 10 which engage a groove 11 around the stem 5, adjacent the rounded end thereof, said groove being of sufficient depth to fully seat the arms therein.

The plate 7 is provided at its central portion with a circular dome 7' into which the end of the stem 5 projects, said dome having slots 8' on opposite sides for the reception of the arms 10 so that the arms can readily enter said groove, the dome forming a guard for the end of the stem, while the plate will be more rigidly engaged with the stem, as the arms will be held against lateral twisting action.

The arms 10, at their point of union with the body portion of the latch, are provided with loops 12, the loops being so arranged as to direct tension against the arms to cause the same to move toward each other, thereby causing the arms to snap into the slots and groove and remain seated therein until outward pressure is directed against the free ends of the arms to operate the same and to disengage them from the channels, which may be accomplished by inserting the finger or other object between the ends of the arm.

In applying the button to use, any suitable instrument is employed for forming an incision in the fabric, after which the stem is introduced through the button and then forced through the opening in the fabric, the plate 7 being then introduced over the end of the stem and moved inwardly until the arms engage the groove in the stem, when the button will be securely locked in engagement with the fabric or garment.

This form of button can be attached to any make of garment or other object requiring buttons and may be transferred from one garment to another as desired.

It will likewise be seen that the button

can be readily attached or removed from the garment and that the same can be manufactured at a minimum expense and further by providing the plate for engagement with the rear face of the fabric, the fabric will be fully protected against enlarging or tearing out at the opening through which the stem of the button projects.

I claim:—

- 10 1. A button of the class described, comprising a button proper formed with a central opening, a removable headed stem disposed through said opening and formed with an annular groove adjacent one end, a plate 15 formed centrally with an externally projecting hollow dome coöperating with said stem, said dome being provided on opposite sides with slots, and a latch carried by and exteriorly of the plate and embodying spring 20 arms yieldingly disposed within the dome slots, said spring arms being each formed with a spring coil therein and adapted to spring into the annular groove of the stem when the end of the stem is inserted through 25 the said plate into the hollow dome thereof between the spring arms.

2. A button of the class described, comprising a button proper formed centrally with an opening, a removable stem having a rounded end disposed through said opening and formed with an annular groove adjacent the rounded end, a plate formed exteriorly with a hollow dome coöperating with said stem, said dome being provided with slots on opposite sides, and a latch 30 carried by and mounted exteriorly of the plate and embodying spring arms each having a spring loop therein, said arms being yieldingly disposed within the dome slots and extending through and beyond the dome, 35 said spring arm adapted to spring into the annular groove of the stem to retain the stem in locking engagement within the dome of said plate.

In testimony whereof I have signed my name to this specification in the presence of two subscribing witnesses.

EMIL TESKA.
